UNITED STATES PATENT OFFICE.

WILLIAM G. STEWART, OF ELKINS PARK, PENNSYLVANIA.

NEEDLE-LOOM.

1,164,137.

Specification of Letters Patent. Patented Dec. 14, 1915.

Application filed March 2, 1915. Serial No. 11,477.

To all whom it may concern:

Be it known that I, WILLIAM G. STEWART, a citizen of the United States, residing at Elkins Park, in the county of Montgomery 5 and State of Pennsylvania, have invented certain new and useful Improvements in Needle-Looms, of which the following is a specification.

My invention relates to the class of looms 10 for weaving narrow cloth or fabrics commonly called tape and braid, wherein the weft threads are projected through the warp sheds by a weft-needle and wherein another device or devices coöperate with the 15 weft-needle to prevent it from withdrawing the weft threads from the warp sheds after the weft threads have been projected therethrough. Looms of this class have been objectionable for the 20 reason that it has been necessary to employ a lay to beat the successive picks of weft threads up to the fell of the cloth, resulting in wearing and breaking the warp threads and preventing the use of 25 certain classes of threads or yarns not having sufficient durability to withstand the wearing action of the reeds in the lay, such, for example, as artificial silk; and for the reason that it has been diffi- 30 cult, if not impossible, to weave a strip of fabric of uniform texture from edge to edge; and for the reason that it has been difficult to bind in the weft threads in the desired manner in which the weft 35 threads shall lie straight across the warp threads, at right angles thereto.

The object of my invention is to overcome these and other objections; and I accomplish my object by the provision of a loom of 40 novel, simple and efficient construction wherein I construct and operate the weft needle in such manner that it operates both as a means to project the weft threads through the warp sheds and also as a means of 45 to beat up or move the successive picks of weft threads into position at the fell of the cloth, thereby dispensing with the employment of a lay and the many objections incident thereto; and I accomplish my object 50 further, by the provision of a novel mechanism, firstly, wherein a fabric of uniform texture from edge to edge may be woven, secondly, wherein a plurality of strips of fabric may be woven on a single loom with 55 less space between adjacent strips than heretofore, thirdly, wherein the devices which

coöperate with the weft needle to bind the weft threads at one edge of the fabric are simplified and improved, fourthly, wherein, less attention on the part of the operator 60 will be required than heretofore, fifthly, wherein less power will be required and higher speed will be attained than heretofore, and, sixthly, wherein many novel and advantageous results are produced. 65

My invented loom consists of the elements and the combinations of them herein-after fully described and claimed.

In the accompanying drawings, illustrating my invention: Figure 1 is a plan view of 70 a portion of a loom embodying my invention. Fig. 2 is a vertical section thereof, on line 2—2 of Fig. 1. Figs. 3 and 4 are sectional details, on lines 3—3 and 4—4 of Fig. 1, respectively, showing one of the weft needles and adjuncts. Fig. 5 is a sectional detail, on line 5—5 of Fig. 1, showing one of the bearings for the needle bars or carriers. Figs. 6, 7 and 8 are diagrammatic views relatively to each other and to the threads during the weaving operation. Fig. 9 is a diagrammatic view showing by a dot-and-dash line the path of the weft-needle relatively to the fabric being woven. 75

Referring to the drawings, the loom frame 85 comprises the end standards 6 connected by the bars 7 and the breast beam 8. The warp threads 9 are drawn from a roller 10 to and over a roller 11, thence to and through the eyes of heddles 12 and thence through or between suitable reeds 13 to the fell of the cloth or fabric being woven, which is drawn over a bar 14 and down under the breast beam 8 to the take-up roller 15. The roller 10 is journaled 90 in suitable bearings on the standards 6, and the roller 11 is journaled in brackets 16 on the standards 6. The heddles 12 are carried in suitable heddle frames 17 which are raised and lowered in the usual well known manner, during the weaving operation, by the usual well known mechanism, which it is not deemed necessary to illustrate or describe herein. The reeds 13 serve to guide the warp threads in proper lateral relation 95 to each other and they are carried in a frame 18 which is supported by brackets 19 on the breast beam 8. The bar 14, over which the finished fabric passes, is supported by suitable blocks 20 on the breast 100 beam 8. The take-up roller 15 is mounted to turn in bearings on the standards 6 and it is 105 110

actuated in the usual manner and by the usual well known devices to take up the finished fabric as rapidly as it is produced, during the weaving operation.

5 The loom herein illustrated, is constructed to weave a plurality of strips of fabric, side by side, as clearly shown in Fig. 1; and for each strip of fabric I employ a weft-needle 21 and a knitting needle 22 which 10 coöperate with each other to weave the weft threads into the fabric, as will be herein-after explained.

Each weft-needle 21 is secured to and projects from an arm 23 which is secured to a 15 common bar or carrier 24 which extends parallel to the breast beam 8, so that the plurality of weft-needles 21 will be bodily moved when the bar 24 is moved. The arm 23 of each weft-needle 21 projects from the 20 bar 24 in the direction of the warp threads laterally adjacent to one strip of fabric being woven, each needle projecting from its arm 23 in a direction substantially parallel to the bar 24 and spaced therefrom, so that 25 the free end of the weft-needle 21 may be moved into and from the warp shed from one side thereof when the bar 24 is moved.

Each knitting needle 22 projects from and 30 is secured to a common bar or carrier 25 which extends parallel to the bar 24, so that the plurality of knitting needles 22 will be bodily moved when the bar 25 is moved, each knitting needle 22 projecting from the bar 25 in the direction of the warp threads 9 35 and laterally adjacent to one side of a strip of fabric being woven, to coöperate with the weft-needle 21 adjacent to the opposite side of the same strip, during the weaving operation, herein-after explained.

40 The carriers or bars 24 and 25 are slideable mounted, one above the other, in bearings 26 on the breast beam 8, so as to be movable horizontally therein. One end of the bar 24 carrying the weft needles 21 is 45 provided with a downwardly-extending end 27 which is engaged by a cam 28 on an inclined shaft 29 which is adapted to turn in bearings 30 on one of the end standards 6. The lower end of the shaft 29 is provided with a bevel gear wheel 31 which co-acts with a similar wheel 32 on a shaft 33 which turns in bearings on the standards 6. The shaft 33 is provided with a gear wheel 34 in mesh with a gear wheel 35 on the driving shaft 36 of the loom, whereby, the shaft 29 and its cam 28 will be rotated during 50 the operation of the loom. The bar 24 is held against the cam 28 by a spring 37 one end of which is attached to the bar 24 and 55 the other end of which is attached to the breast beam 8. It will thus be seen that when the shaft 29 is rotated, the bar 24 will be reciprocated or moved back and forth, by the cam 28 and spring 37, longitudinally 60 or in a direction transversely to the warp 65

threads 9 to move each weft-needle 21 into and from the adjacent shed of warp threads. The bar 24 is not only moved longitudinally, as just described, but it is also moved transversely or in the direction of the warp 70 threads 9 to move each weft-needle 21 toward and from the fell of the cloth or strip of fabric being woven, for a purpose herein-after explained; and to effect this movement of the bar 24 I provide it with rollers 38 75 which engage cams 39 on a shaft 40 turning in bearings 41 on the breast beam 8. The rollers 38 are held against the cams 39 by springs 42 each of which has one end secured to the bar 24 and the other end secured to the breast beam 8; and the shaft 40 is actuated from the shaft 29 by coacting bevel gear wheels 43 and 44 secured to the shafts 29 and 40, respectively. The bar 25 carrying the knitting needles 22 is only 80 moved transversely or in the direction of the warp threads to reciprocate the knitting needles 22 longitudinally, and for this purpose I provide the bar 25 with rollers 45 which engage cams 46 on the shaft 40 and 90 which are held against the cams 46 by springs 47 each of which has one end secured to the bar 25 and the other end secured to the breast beam 8.

The weft threads of each strip of fabric 95 being woven are formed of a continuous thread 48 which is drawn from a spool or bobbin 49 supported by a bracket 50 which projects from a bar 51 extending between the end standards 6. Each thread 48 passes 100 from its spool 49 to and through a pair of tension disks 52 on a bracket 53 secured on the bar 24 which carries the weft needles 21, thence through the eye of a spring take-up arm 54 projecting from a pin on the bracket 105 53 and thence to and through the eye 55 of the weft-needle 21, the arm 54 acting to take up the slack thread during the reverse movement of the weft-needle 21.

Each weft-needle 21 is downwardly inclined from its arm 23, as shown in Fig. 4, and has its free end portion bent or extended toward the fell of the cloth 56, as shown in Fig. 9, for purposes herein-after explained; and each weft-needle 21 has a raised portion 57 adjacent to its eye to permit a part 110 of the adjacent knitting needle 22 to pass between the body of the weft needle 21 and the thread extending from the weft-needle eye 55 to the fabric, during the weaving 115 operation.

The knitting needles 22 I employ are, preferably, beard needles, and these needles are so operated with relation to the weft-needles 21 that upon the reverse stroke of the beard 120 needles, the beards thereof will engage the weft-needles and be closed thereby to cause the shedding of loops of thread from the knitting needles 22, and I further insure this shedding of the loops by extending each 125 130

knitting needles 22 through a notch 58 in the bar 14, so that the bar 14 will engage a loop extending around a needle 22 and shed the loop as the needle 22 is drawn back 5 through the notch 58.

The operation of the loom is as follows: The heddle frames 17 are raised and lowered after each pick of the loom to cross the warp threads 9, in the usual manner; and the 10 cloth or finished fabric 59 is wound upon the take-up roller 15 as rapidly as it is produced, in the usual manner. At each pick of the loom the bar 24 carrying the weft-needles 21 is moved in the direction of the 15 warp threads 9 and also transversely thereto, and the bar 25 and knitting needles 22 are moved in the direction of the warp threads, as previously explained. During this operation, a pair of weft threads 60 is 20 inserted into the warp shed of each strip of fabric and a loop formed by the pair is drawn through a loop 62 formed by the last preceding pair of weft threads 63 which were inserted in the warp shed during the 25 last preceding pick of the loom, as shown, in Figs. 7 and 8, and thus the successive pairs of weft threads are bound into the fabric of each strip at the edge thereof opposite to the side of the strip from which they are inserted, thereby forming a selvage and preventing the reverse movements of the weft-needles 21 from withdrawing the weft threads from the warp sheds.

As previously stated the weft-needles 21 35 are all bodily operated by the bar 24, and the knitting needles 22 are all bodily operated by the bar 25; and, therefore, I shall describe only the operation of one weft-needle and one knitting needle with relation 40 to each other and to the threads of one strip of fabric. Starting with the needles in the position shown in Fig. 6, in which the weft-needle 21 is about to enter the warp shed after the crossing of the warp threads following the preceding pick, the weft needle 21 is advanced directly through the warp 45 shed, through the portion 64 of the path 65, shown in Fig. 9, to the position shown in Fig. 7. During this movement of the 50 weft-needle 21, thread is drawn from the overhanging spool 49 through the tension device 52 and through the weft-needle-eye 55 and the two weft threads 60 are inserted into the warp shed, as shown in Fig. 7; and, 55 during this movement of the weft-needle 21, the knitting needle 22 moves forward or in the direction of the arrow in Fig. 6, to the position shown in Fig. 7. The needles 21 and 22 now start their reverse movements in 60 the direction of the arrows in Fig. 7; and, during such reverse movements, the beard 66 of the knitting needle 22 passes between the body of the weft-needle and the thread 65 extending therefrom to the opposite side of the fabric and takes a loop 67 from the

thread 60 and draws the loop 66 back through the previously formed loop 62, as shown in Fig. 8, the beard 66 of the needle 22, during its movement, engaging the bottom of the weft needle 21 and being closed thereby and thus caused to enter the previously formed loop 62 which is shedded from the needle 22 as it recedes. This shedding of the loop 62 is insured by the plate 14 as the needle 22 recedes through the notch 58 in the plate, the notch 58 being only large enough to receive the needle 22 and the loop of thread engaged by the hooked end thereof. Just after the weft needle 21 reaches the position shown in Fig. 7 it moves toward the fell of the cloth or fabric and continues its reverse movement through the portion 68 of the path 65 shown in Fig. 9, thereby moving the threads 60 back into proper position at the fell of the cloth as the weft needle 21 moves back to the position shown in Fig. 6 for a succeeding operation or another pick, after the crossing of the warp threads 9 following the insertion of the weft threads 60. Thus the weaving of the fabric 90 continues by successive operations, the cams 28, 39 and 46 being formed and operated to effect the movements of the needles 21 and 22 hereinbefore described. The chain of loops formed by the knitting needle 22 form 95 a selvage at one edge of the fabric, and a selvage is formed at the opposite edge of the fabric by the loops which connect the adjacent warp sheds, as clearly shown in Figs. 6, 7 and 8.

As previously explained, each weft-needle 21 is arranged on an incline, as shown in Fig. 4. The purpose of this is to permit the supported end of one weft-needle 21 to move over and above the next adjacent strip of fabric or its warp shed, thus reducing the space between adjacent strips of fabric to a minimum and enabling me to produce a large number of strips of fabric on a comparatively small loom.

I claim:

1. In a needle loom the combination of the frame thereof, means to support and actuate the warp threads, a weft-needle, means to support the weft-needle and to project it through the warp shed and to move it to and from the fell of the cloth, said weft needle acting to project the weft threads through the warp shed and thereafter acting to move the weft threads into 115 position at the fell of the cloth, and means co-operating with the weft-needle to form a selvage.

2. In a needle loom the combination of the frame thereof, means to support and actuate the warp threads, a weft-needle, means to support the weft-needle and to project it through the warp shed and to move it to and from the fell of the cloth, said weft needle acting to project the weft threads 125

through the warp shed and thereafter acting to move the weft threads into position at the fell of the cloth, a knitting needle, and means to support the knitting needle and to actuate it in conjunction with the weft-needle to form a chain of stitches.

3. In a needle loom the combination of the frame thereof, means to support and actuate the warp threads, and means to insert weft threads into final position in the warp shed, the last named means including an element movable into and from the warp shed from one side thereof and means to move said element to and from the fell of the cloth, said element acting to move the weft threads into position at the fell of the cloth after being inserted into the warp shed.

4. In a needle loom the combination of the frame thereof, means to support and actuate the warp threads, a weft-needle, means to support and actuate the weft-needle, and means coöoperating with the weft needle to form a selvage, the last named means including a beard knitting needle, and said weft needle operating to close the beard of the knitting needle during the operation thereof.

5. In a needle loom the combination of the frame thereof, means to support and actuate the warp threads, a weft needle, means to support the weft-needle and to project it into and withdraw it from the warp shed and to move it toward and from the fell of

the cloth, said needle completing its movement toward the fell of the cloth while it extends entirely through the shed and serving to lay the weft against the fell of the cloth.

6. In a needle loom, the combination of the frame thereof, means to support and actuate the warp threads, a weft needle, means to support the weft-needle and to project it into and withdraw it from the warp shed and to move it toward and from the fell of the cloth, said needle moving substantially parallel to the fell of the cloth while being withdrawn from the shed and serving to lay the weft against the fell of the cloth.

7. In a needle loom, the combination of the frame thereof, means to support and actuate the warp threads, a weft needle, means to support the weft-needle and to project it into and withdraw it from the warp shed and to move it toward and from the fell of the cloth, said needle having its free end extending from the body thereof toward the fell of the cloth and moving substantially parallel to the fell of the cloth while being withdrawn from the shed and serving to lay the weft against the fell of the cloth.

In testimony whereof I affix my signature in presence of two witnesses.

WILLIAM G. STEWART.
